UNITED STATES PATENT OFFICE.

PIERCE X. JOHNSON AND FRANK J. SUPER, OF PORTLAND, OREGON, ASSIGNEES TO
JOHNSON-BRADFORD SAFE COMPANY, A CORPORATION OF OREGON.

SAFE-DOOR.

1,235,808.

Specification of Letters Patent.

Patented Aug. 7, 1917.

Application filed November 16, 1912. Serial No. 731,801.

To all whom it may concern:

Be it known that we, PIERCE X. JOHNSON and FRANK J. SUPER, citizens of the United States, residing in the city of Portland, county of Multnomah, and State of Oregon, have invented certain new and useful Improvements in Safe-Doors, of which the following is a specification.

Our invention relates to safe doors, and 10 more particularly to an improved construction and arrangement of doors for safes and vaults, with operating mechanism therefor, whereby we secure a stronger door with a more nearly perfect opening, closing and 15 locking operation.

Among the salient objects of this invention are,—

To provide in a safe or vault door a construction whereby a plurality of door sections can be made of the hardest of manganese steel, with a new and practical means for securing said door sections together, and for mounting thereupon and securing thereto the locking bolts and the bolt-manipulating and bolt-locking mechanisms; 20 to provide in combination with a safe or vault door, a supporting hinge or yoke therefor with improved connections thereto, whereby to make it possible for a very thick 25 door to be moved in a straight line out of and into the door opening before being swung upon its supporting hinge or yoke. Other objects and features of improvement 30 will be apparent from the description of one 35 embodiment of the invention hereinafter contained, taken with the accompanying sheets of drawings forming a part hereof, and in which,—

Figure 1 shows a face or front elevation of 40 a safe embodying our invention;

Fig. 2 shows a fragmentary side elevation thereof, with parts broken away and a part shown in section, taken on line 2—2 of Fig. 1;

Fig. 3 is a top plan view thereof;

Fig. 4 is a plan view with part in section, taken on line 4—4 of Fig. 2;

Fig. 5 is a fragmentary view, partly in section, taken on line 5—5 of Fig. 1;

Fig. 6 is an inside or back view, in elevation, of a door embodying our invention,

with the upper halves of the two innermost door sections cut away;

Fig. 7 is a vertical sectional view, partly in elevation, through a safe door embodying 55 our invention, as if taken on line 7—7 of Fig. 6, with parts broken away to reduce the figure;

Fig. 8 is a fragmentary sectional view, taken on line 8—8 of Fig. 6; 60

Fig. 9 is a detail, showing one method of spacing the safe body sections to receive the door;

Fig. 10 is an inside or back view of the outermost section of a door embodying our 65 invention;

Fig. 11 is a vertical sectional view taken on line 11—11 of Fig. 10;

Fig. 12 is an enlarged fragmentary cross sectional view through the middle of a door, 70 similar to the middle portion of Fig. 7;

Fig. 13 is an inner face view taken on the joint line 13—13 of Fig. 12;

Fig. 14 is an enlarged fragmentary cross sectional view through the upper portion 75 of a door, similar to the upper portion of Fig. 7;

Fig. 15 is an end view of parts shown in Fig. 14;

Fig. 16 is a sectional view taken on line 80 16—16 of Fig. 14;

Fig. 17 is a sectional view taken on line 17—17 of Fig. 14.

As hereinbefore stated, an object of this invention is to make a heavy safe-door, in 85 sections, of the hardest of manganese steel, with the sections so secured together that they can be readily assembled and taken apart, when necessary, and the whole so hingedly supported to the safe or vault body 90 that it can be readily and correctly opened and closed at will. The door is particularly adapted for the burglar proof safe shown and described in United States Letters Patent to P. X. Johnson No. 1,026,207, of May 95 14, 1912, in which the body of the safe is made of a plurality of perforated body sections mounted one within the other at a space apart, in the manner indicated in part in Fig. 7.

Referring now to Figs. 1, 2 and 3, we will 100 first describe our improved hinge support

for a door of the character referred to. In the drawings A designates the safe body into which the door B fits. The door A is supported upon a yoke member C of the usual form, but which is attached to the door by means of a double hinge, above and below, as at C¹ and C², connected together by a connecting portion C³ formed as a part thereof, as shown in Fig. 2, said double hinge comprising two short arm like portions hingedly attached at their outer ends to the yoke C, as at C⁴, and hingedly connected to the door at their inner ends, as at C⁵. We believe we are the first to hinge a heavy safe door upon a double hinge in such manner that it is possible for the door to be moved out of the safe body in a straight line as the yoke moves upon its hinge connection to the safe body.

20 The door is moved inwardly and outwardly by the usual mechanism, comprising a hand wheel 1, which operates a shaft 2, provided at its opposite ends with disks 3, provided with the crank pins 4—5, which engage in the usual socket pieces 6—7. In order to prevent any lateral movement of the door upon its hinge support when open, we have provided the crank pin 5 with a nut 8 and a spacing nut 9, whereby it is moved in the socket 10 in the block or piece 7, but is not movable longitudinally of its length, thereby preventing any lateral or side movement of the door in either direction upon its double hinge support when open. When the bolt manipulating lever 11 is moved to the left, as indicated in dotted lines, to withdraw the bolts of the door in a manner hereinafter again referred to, the hand wheel 1 is revolved and operates through the shaft 2, the disks 3 and the crank pins 4 and 5 to move the door directly outwardly sufficiently far to permit of a free and easy movement of the door upon its hinge or yoke without in any way interfering with the sides of the door opening, and because of the double hinge joint, with the short supporting arms C¹ and C², a very thick door can be moved in a straight line outwardly sufficiently far to clear the door opening when swung, instead of commencing a swinging movement about the yoke axis as soon as the door is started out of its closed position.

55 The double hinge is secured to the door B, which, it is understood, is made of the hardest of manganese steel, by means of pairs of inturned lugs, as 12—12, formed or cast upon the door face at the time it is made. Between these lugs 12—12 is secured a filling piece or plug of softer steel, as 13—13, to which it is possible to attach the inner ends of the double hinges. The side pieces 6 and 7 which receive the disk crank pins 4 and 5, are secured to the sides of the

safe body in the same manner, as are also the supporting blocks or pieces in which the shaft 2 is mounted.

Referring now to Figs. 6 to 16, we will next describe the construction of the door, which is here shown to be composed of three parts or body sections, B¹, B² and B³. Said door sections are provided, respectively, upon their inner sides, formed as an integral part thereof, with what we will call bolt-receiving frame portions B⁴, B⁵ and B⁶. Said door section B¹ is also provided upon its inner face with sets of inturned lug members, as B⁷—B⁷, Fig. 8, formed thereupon for a purpose hereinafter more particularly referred to. The outermost door section B¹ is provided with two U-shaped pocket lugs B⁸, formed integrally therewith for a purpose hereinafter mentioned. A carrying plate B⁹ of softer material than the manganese steel of which the door section is made, is mounted upon the inner side of said door section for the purpose of supporting the bolt- and lock-manipulating mechanism. This carrying plate B⁹ is supported on the outer door section by means of holding pieces B¹⁰, of which there are four, set edge-wise and secured to the door by means of bolts B¹¹, having heads which fit between the inturned lug members B⁷, as clearly indicated in Figs. 8, 10 and 11. Said carrying plate B⁹ is supported to the inner edges of said holding members B¹⁰ by means of bolts B¹². Locking bolts, designated D, of which there are three at each side and two at each end of the outermost door section B¹, are slidably mounted through the integral frame member B⁴, and also through the holding pieces B¹⁰, as indicated. These bolts are operated by means of movably mounted bolt-operating members D¹ and D², there being two of each, and all four of which are operatively connected by means of arm portions at their inner ends to a disk-like member E, mounted upon a shaft or bolt F, and by means of which disk-like member E said bolt operating members D¹ and D², and said bolts D, are simultaneously drawn inwardly or moved outwardly out of and into locking positions. It will be noted that the bolt-operating members D¹ are cut out in their middles so as to slidably fit around the U-shaped lug members B⁸, formed upon the inside of the door section B¹.

A pair of supporting or connecting bolts, as G—G, provided with heads G¹—G¹ which fit into the U-shaped pocket lugs B⁸, serve to connect and support the three door sections B¹, B² and B³ together, as indicated in Figs. 7, 10 and 14, and particularly the latter figure.

Door section B² is constructed very similarly to door section B¹, except that it has

no U-shaped pocket lugs B^8 , as has section B^1 , and has no inturned lugs B^7 . A carrying or supporting plate of softer material, designated B^{13} , is mounted upon the inside of 5 said door section B^2 , and is provided with suitable openings therethrough to receive the connecting bolts $G-G$, and with a central opening therethrough so as to fit around the middle thicker portion of the door section, 10 as shown, Figs. 7 and 12. This supporting or carrying plate B^{13} is secured to the door section B^2 by means of the supporting and connecting bolts $G-G$ in the following manner. Referring to Fig. 14, a 15 nut B^{14} , made in halves and exteriorly threaded, is placed upon the bolt G next to the enlarged portion G^2 thereof, and an interiorly threaded nut B^{15} is secured thereupon and against said supporting plate B^{13} , 20 as shown, forcing the same against the door section B^2 , which is engaged at its outer side by the enlarged portion G^3 of said supporting bolt G . Both bolts $G-G$ are extended through and secured to the inner 25 door section B^3 in the same manner. Bolt G , from the enlarged portion G^3 , is adapted to pass through the openings in the door section B^2 and in the supporting plate B^{13} until its enlarged portion G^3 engages the 30 outer side of said door section B^2 . The two-part nut B^{14} is then placed around said bolt G and the nut B^{15} is screwed thereupon in the manner indicated, Figs. 7 and 14.

Locking bolts H , of which there are three 35 at each side of door section B^2 , and two at each end thereof, the same as in case of door section B^1 , are moved in the same manner, as by means of bolt operating plates H^1 , connected to and operated by a disk-like member H^2 , similar to the disk-like member E . Said disk-like member H^2 is mounted upon a bolt or shaft H^3 , which carries at its outer end a disk H^4 positioned adjacent the disk-like operating element E and with which it 45 is connected by means of a crank pin H^5 , shown in dotted lines and in section, Figs. 12 and 6. This crank pin H^5 , between the disk member E and the disk H^4 , constitutes the only connection between the bolt or shaft H^3 and the bolt or shaft H^3 , and by it the revolving of the disk E operates to revolve disk H^4 , the shaft H^3 and the disk-like member H^2 , connected to the operating plates H^1 , which move the bolts H simultaneously. 50

Door section B^3 is similar to section B^2 , but is provided with three lock bolts at each of its sides and none at its ends. A carrying or supporting plate B^{16} of softer material is secured thereto in the same manner as carrying plate B^{13} is secured to door section B^2 , that is, by means of two-part nuts B^{17} , and a holding nut B^{18} , Fig. 14. The locking bolts, designated as I , are moved in the same manner as are the other locking

bolts and simultaneously therewith, by 65 means of bolt operating plates I^1 I^1 , connected to and operated by means of a disk like member I^3 , mounted upon a bolt or shaft I^4 . Mounted upon the end of said shaft or bolt I^4 is a disk-like member I^5 70 which faces and rests in register with the disk-like member H^2 , and with which it is connected by means of a crank pin I^6 , shown in dotted lines in Fig. 12 and in section, Fig. 13. 75

Referring to Figs. 7 and 6, an operating bolt 14, upon the outer end of which the operating lever 11 (Fig. 1) is mounted, and upon the inner end of which an operating arm 15 (shown in dotted lines in Fig. 6) 80 is mounted to turn therewith, and having a slot and pin connection with the bolt operating plate D^2 , whereby the movement of said operating lever 11, turns said shaft 14, and rocks said arm 15 in opposite directions, thereby moving the plate D^2 , which is connected to and turns disk-like member E , through which all of the bolt operating plates D^1 and D^2 are turned, and the bolts D are moved inwardly and outwardly at 90 will. The operation of the disk-like member E , through the crank pin connection at H^5 (Figs. 6, 7 and 12), operates disk H^4 , shaft H^3 to which it is keyed, as at H^6 , and disk H^2 , through which the lock bolts H , of door section B^2 are moved inwardly and outwardly. The movement or operation of disk like member H^2 , through crank pin connection I^6 , operates disk I^5 and shaft I^4 , to 95 which it is keyed, as at I^7 , and disk I^3 , by means of which the lock bolts I of the innermost door section B^3 are moved inwardly and outwardly, simultaneously with the other door bolts. 100

Door sections B^1 , B^2 and B^3 , as hereinbefore stated, are made of manganese steel and in order to provide suitable bearing openings therethrough for the bolt operating shafts F , H^3 and I^4 , the inner door sections B^2 and B^3 , through which the operating or supporting bolts or shafts H^3 and I^4 must pass, are cored in their formation with suitable filling cores, as 16, of softer steel which can be bored for the reception of the bolts H^3 and I^4 . 105

The yoke C and its supporting hinge is secured to the door edge of the safe body by means of inturned lugs, as 17-17, with a softer filling piece or core 18, as herein described with reference to the inturned lugs 12-12. 110

Attention is also called to the fact that the inwardly projecting frame portions, formed on the door sections, B^4 , B^5 and B^6 , and through which the locking bolts D , H and I , project, are cored with softer material cores which can be bored out smoothly to receive the locking bolts. This is indi- 115 120 125

cated by the double dotted lines in Figs. 6 and 7, and will be readily understood.

We are aware that modifications can be made in the drawings illustrating our improvements without departing from the spirit of the invention, and we do not, therefore limit the invention to the described illustrations, except as we may be limited by the hereto appended claims.

10 We claim:

1. A safe door comprising a plurality of door sections of hard metal secured together flatwise at a space apart, supporting or carrying plates of softer material secured to 15 the inner sides of said door sections, bolt and locking mechanisms supported upon said plates and means for operating the same, substantially as described.

2. In a safe door, a plurality of door sections, lug elements formed upon said door sections connecting bolts for securing said sections together, locking bolts and bolt-manipulating mechanism supported upon said door sections by means of said lug elements.

3. In a safe door, a plurality of door sections, said door sections being formed with openings therethrough, connecting and supporting bolts for supporting the inner sections to the outer section, said outer section having formed thereon attaching and supporting lug elements for said bolts.

4. In a safe door, a plurality of door sections with integrally formed frame portions with bolt openings therethrough, supporting lugs formed integrally upon the inner face of one of said sections, bolt-manipulating mechanism supported to said door section by means of said lugs, connecting bolts through some of said door sections and supported at their ends by said lug elements formed upon said door section.

Signed at Portland, Multnomah county, Oregon, this 8th day of November, 1912.

PIERCE X. JOHNSON.
FRANK J. SUPER.

In presence of—

JAMES N. DAVIS,
WALTER C. SMITH.
